UNITED STATES PATENT OFFICE

KARL EMIL WENZLAWSKI, OF GALVESTON, TEXAS

ELECTRIC SWITCH

Application filed May 11, 1928. Serial No. 277,030.

My invention relates to electric switches for closing electric light or power circuits. It is particularly adapted for use in light circuits in buildings.

5 My device is designed to prevent danger in case of a short circuit in the lighting circuit of a building. It is a more or less common occurrence when a fuse is blown out in the lighting circuit, due to overload, or to lightning, or other causes, for the attendant in charge of the building to substitute a new fuse in place of the blown out one and again close the circuit. Sometimes a proper fuse is not available and coins, or nails, or pieces 15 of wire are substituted for the fuse. If it happens that there is a short circuit in the building, there is then danger of fire where the short circuit occurs.

It is an object in my invention to provide 20 a switch for the control of building circuits of this kind wherein provision is made to prevent the closing of the switch when there is a short circuit in the building.

The invention consists in the provision of 25 an electrically operated device which will be actuated to move into the path of the switch and prevent its closing where the resistance of the lighting circuit has been cut out by means of the short circuit.

30 Referring to the drawing herewith, Fig. 1 is a diagrammatic plan view of a switch embodying my invention. Fig. 2 is an elevation of the stop arm whereby the switch is prevented from closing, parts of the apparatus being removed for greater clearness. Fig. 3 is a detailed view of the electromagnet and the operating arm whereby the stop mechanism is operated.

I contemplate the use of my invention with 40 the ordinary type of two blade knife switch used in the lighting circuit of houses and other buildings. I have shown a switch employing two blades 1 and 2, hinged to terminals 3 and 4 respectively, the free ends of said blades being connected by an insulating member 5 having a handle 6. On the forward side of the handle is a short arm 37 projecting into the path of a stop member which will be later described.

45 50 The switch is mounted upon a base 7 in the

usual manner. The main light circuit 8 is connected through fuses 9 to the posts 10 and 10' and it will be seen that there are two posts 10 and 10' connected with the contact members 11 in which the blades 1 and 2 of the switch engage when in closed position.

55 The circuit from the post 10 is connected at 12 to a transformer 13 by means of which the voltage is materially reduced. The opposite post 10' is connected by a wire 14 to the terminal 12' through the transformer.

60 The circuit from the transformer is carried through a wire 15 at one side to a spring arm 16, the shape of which is best shown in Fig. 2. It extends upwardly and has a curved contact member 17 at its upper end which extends in to the path of the blade 2 of the switch and contacts therewith when the blade 70 is being moved to or from its closed position.

65 The other wire 17' of the auxiliary circuit is connected through an electromagnet 18 to a post 19 at the terminal 3 of the house circuit.

70 The electromagnet 18 is of ordinary construction and is adapted to move a spring 75 arm 20. Said spring arm is mounted upon a post 21 on the inner side of the base 7 and is connected through an arm 23 of magnetic material which extends forwardly of the base and is connected at its forward end to a 80 link 22. This is a pivotal connection and the lower end of said link 22 is pivotally connected at 23 with the arm 24 of a bell crank lever 25, pivotally supported upon a pin 26 mounted upon a block 27 on the base. The 85 upper arm 28 of the bell crank lever extends normally upward and has a wide notch or recess 29 therein, the sides of said notch being beveled outwardly at 30. This arm is intended to act as a stop to engage the arm 37 90 upon the handle as previously noted.

95 In the operation of this device the auxiliary circuit is regulated by the transformer 13 to be of such small voltage that when the light circuit through the wires 31 is connected in the usual manner through the resistance of the lights the current will be of insufficient strength to actuate the electromagnet 18. When, however, the lighting circuit is grounded in some manner, the resistance of 100

the lights is cut out so that the strength of the auxiliary current will be sufficient to actuate the magnet to move the stop member.

Thus when there is a short circuit formed in the lighting circuit 31 and a fuse has been blown out the operator may replace the fuse and attempt to close the switch. If a short circuit still remains in the house circuit the current through the magnet in the auxiliary circuit will be of sufficient value to energize the magnet to move the arm 23 downwardly. This will, through link 22, move the arm 25 and throw the stop member 28 into position directly beneath the arm 37 upon the handle 15 and prevent its closing. It is to be noted that the auxiliary circuit is not closed to energize the magnet until the blade 2 of the switch contacts with the member 16. This will throw the stop member into position 20 and hold it in that position until the stop arm 37 engages therewith. It will hence be impossible to close the switch until the short circuit in the house lighting circuit has been repaired.

25 The advantage of this arrangement will be obvious to those skilled in the art. The danger from fire through short circuits in a building will be practically eliminated.

Having thus described my invention, what I claim as new is:

30 1. A safety switch comprising a two blade switch adapted to connect the two wires of a main light circuit to two terminals of a house lighting circuit, in combination with an auxiliary circuit from said light wires, a transformer in said auxiliary circuit, a resilient contact positioned in the path of movement of one of said switch blades, connected with one of the wires of said auxiliary circuit, the other 35 of said auxiliary wires being connected through an electromagnet to the terminal of the house circuit remote from the said resilient contact member, and means actuated by said electromagnet when said switch contacts with said resilient contact to prevent the closing of said switch when there is a short circuit on the house circuit.

35 2. A safety switch including a two blade switch adapted to connect the wires of a main circuit to the terminals of a lighting circuit in combination with an auxiliary circuit of comparatively small voltage, said auxiliary circuit having one terminal thereof forming a wiping contact with one blade of said switch when said blade is partly opened, the other terminal of said auxiliary circuit connecting to the terminal of the other blade of said switch, an electromagnet in said auxiliary circuit, and means actuated by said electromagnet to move into the path of said switch and prevent its closing when there is a short circuit in said circuit.

30 3. A safety switch including a two blade switch adapted to connect the wires of a main circuit to the terminals of a house lighting

70 circuit in combination with an auxiliary circuit of comparatively small voltage said auxiliary circuit having one terminal thereof forming a wiping contact with one blade of said switch when said blade is partly opened, the other terminal of said auxiliary circuit connecting to the terminal of the other blade of said switch, an electromagnet in said auxiliary circuit, and an arm operated by said electromagnet, a hinged stop member, and a connection between said stop member and said arm whereby said stop member may be moved into the path of said switch and prevent its closing.

75 4. A safety switch for use in a house lighting circuit, including an auxiliary circuit of comparatively small voltage, connected in said house circuit, said auxiliary circuit having one terminal positioned to engage a blade of said switch when said switch is moving to closed position, an electromagnet in said auxiliary circuit, and a stop arm operated by said magnet to move into the path of said switch when there is a short circuit in said house circuit, to prevent the closing of said switch.

80 5. A safety switch for use in a house lighting circuit, including an auxiliary circuit of comparatively small voltage, connected in said circuit, said auxiliary circuit having one terminal positioned to engage a blade of said switch when said switch is moving to closed position, an electromagnet in said auxiliary circuit, and an arm operated by said electromagnet when said house circuit is short circuited and a stop member moved by the operation of said arm into the path of said switch to prevent its closing.

85 6. A safety switch for use in a house lighting circuit, including an auxiliary circuit of comparatively small voltage, connected in said house circuit, said auxiliary circuit having one terminal positioned to engage a blade of said switch when said switch is moving to closed position, an electrically operated device in said auxiliary circuit adapted to be energized only when the said house circuit is short circuited, and a stop arm adapted to be moved by said electrically operated device to prevent closing of said switch when said switch engages said terminal of said auxiliary circuit.

90 In testimony whereof I hereunto affix my signature this 5th day of May, A. D. 1928.

KARL EMIL WENZLAWSKI. 120
